APPARATUS AND METHOD OF TREATING
BULK MATERIAL

Franklin S. Smith, New Haven, Conn.

Application May 14, 1938, Serial No. 208,029

26 Claims. (Cl. 21—54)

This invention relates to the treatment of materials and more in particular to the art of and apparatus for the electrical treatment of materials for purposes such as the destruction of 5 "insect life," which term as herein used includes the egg, larva, pupa, and adult stages of insects.

Among the objects of this invention is the provision of practical apparatus of simple and durable construction and efficient and dependable 10 action. Further objects are to provide apparatus of the above nature for avoiding an explosive mixture of air and dust, for providing and regulating a desired electrical potential, for maintaining certain predetermined conditions within 15 the zone where the material is treated, for removing ozone and the like from the finished product, and for the prevention of excessive heat at certain points.

Other points are to provide practical methods 20 or arts for achieving the above aims which may be readily carried on and shall be characterized by certainty of the desired results. Other objects will be in part obvious and in part pointed out hereinafter.

25 The invention accordingly consists in the features of construction, combinations of elements, arrangements of parts and in the several steps and relation and order of each of the same to one or more of the others, all as will be illustratively described herein, and the scope of the 30 application of which will be indicated in the following claims.

In the drawings:

Figure 1 is a view partly in elevation and partly 35 broken away, disclosing the general assembly of the apparatus;

Figure 2 is a plan view of the lower electrode; and

Figure 3 is an enlarged sectional view of a 40 portion of Figure 1 showing the details of construction of the parts associated with the treatment zone.

This application discloses mechanisms and processes of operation which are likewise disclosed in my co-pending application, Serial No. 150,522, filed June 26, 1937, entitled, "Apparatus and method of treating bulk material." Certain 45 details of construction disclosed herein may be more clearly understood by referring to that application, the mechanisms and processes disclosed herein being in some respects improvements upon those disclosed in that application.

Certain broad features of this invention contemplate the continuous treatment of materials 50 by high-potential electrical discharges through a

gaseous dielectric and the provision of a method and apparatus for carrying on this treatment with safety in a thoroughly efficient and practical manner. An object of this invention is to provide for the treatment, in the above-mentioned manner, of materials such as cereals, seeds, grains, corn, beans, etc. 5

This treatment is especially effective in completely destroying the insect life of all of the various insects of the type which infest products 10 of relatively small particle sizes, such as coarsely milled cereals, semolina, farina, grits, etc. However, in the treatment of products, it has been found that the desirable characteristics, such as 15 viability of seeds, color, and baking properties of flour, etc., are unimpaired.

Treatment such as that contemplated in the present invention is particularly important in milling or similar operations where insect life is continually being introduced into the milling machinery by infested grain. Under such circumstances, certain eggs and small larvae are not destroyed during the milling process, but often 20 lodge within the equipment and form foci of infestation where they propagate and spread to the finished material. However, if the grain, or other material, entering the milling equipment is treated 25 in accordance with the teachings of this invention, this insect life will be destroyed and infestation within the equipment will be substantially 30 lessened if it is not completely eliminated.

In the present embodiment, means is provided to pass the grain or other material between two electrodes through an area which is termed the "treatment zone." A relatively high-frequency, 35 high electrical potential is maintained across the electrodes with the result that when the material passes through the zone, an electrical discharge occurs between the electrodes. It has been found that this discharge seeks out and destroys insect 40 life of the nature referred to above.

Very satisfactory results have been obtained with the use of a pair of annular, horizontally positioned, electrodes, the upper electrode being stationary, and the lower electrode being rotatable. 45 During operation, the grain or other material is passed upon the upper surface of the rotatable electrode near its center and moves outwardly due to centrifugal force so that it is thrown through the treatment zone. 50

The present embodiment differs from that of the above-mentioned co-pending application in the details of construction of the elements forming the treatment zone and the parts associated therewith, and in the process of treatment with- 55

in the zone. Among other differences, the present treatment zone is somewhat the shape of the outer rim of an inverted dish or the vertical wall of a truncated cone. Thus, in the present embodiment, the material moves through the treatment zone along a curvilinear path in a manner similar to that disclosed in the above mentioned co-pending application, but at the same time it tends to fall, with the result that the curvilinear path of the material is a three-dimensional curve.

Furthermore, in the present embodiment the treatment zone has a greater thickness at its inner edge than at its periphery and is thus somewhat wedge-shaped in radial cross-section. Considering, however, the treatment zone as an extended opening with a cross-sectional area with a height equal to the thickness of the treatment zone and a length equal to its diameter, the thickness of the zone decreases from the inner edge to the periphery as the effective length of the zone increases. Thus, as the material moves outwardly through the treatment zone and tends to spread fan-like radially, it moves between the converging upper and lower walls of the zone and is confined between restricted vertical limits. Under some conditions of usage this feature is important in obtaining efficient and dependable sterilization, as will be more fully explained hereinafter.

Under certain conditions, dust accompanying or forming part of the material being treated, might be so distributed in the oxygen present to form an explosive mixture. However, when desirable, an additional quantity of air, or other gaseous dielectric, such as carbon dioxide, is mixed with the material being treated immediately prior to its passage through the treatment zone; thus, the dust concentration is brought down below that necessary to form an explosive mixture.

When the material being treated is surrounded by air, the corona-like discharges produce ozone and certain oxides, such as oxides of nitrogen, all of which shall be referred to as "air-ionization products". By providing means for blowing air through the treatment zone with the grain and then providing means for removing air from the machine, the air-ionization products are effectively removed from the treatment zone, and the machine, and, at the same time, heat produced incident to the treatment process is removed from the machine.

The general construction of the illustrative embodiment herein set forth is shown in Figure 1 where it will be seen that the apparatus is mounted upon a frame of rectangular tubing which includes three pairs of vertical posts 4, the tops of the posts of each pair being connected by a cross bar 11. Mounted upon cross-bars 11 is the upper housing ring 6 of a casing supporting frame. The casing supporting frame provides mounting means for the entire casing and also includes four downwardly extending arcuate brace plates 203, supporting a lower housing ring 3, across which extend two horizontal rails 5. Attached to the under side of lower housing ring 3 is a funnel-like hopper 1, which receives the treated grain and directs it into an outlet conduit 2.

Mounted in a shoulder on the top inner edge of upper housing ring 6 is a cover rim 8, which carries cover 7. The flat top of cover 7 supports the electrode structures, the air blower means, the grain inlet means, and other elements, including

the high voltage transformer, all in a manner that will fully appear below.

Brace plates 203 of the casing supporting frame are positioned as shown, there being one on each side of the apparatus (shown in section), and two in the back. These plates 203 divide the space between housing rings 3 and 6 into four arcuate openings through which access may be had to the interior of the machine. One of these arcuate openings extends around the entire front of the machine.

Normally closing these arcuate openings and overlapping housing rings 3 and 6, is a band 10, which is tightened and, thus, held in position by clamping means (not shown), attached to flanges on its ends. The ends of band 10 are positioned along the side of one of the brace plates 203 and in this manner a substantially sealed casing is formed of cover 7, hopper 1, and band 10. When desirable, band 10 may be loosened and removed by slipping it down where it may be rested upon lugs 211 on posts 4.

Cover 7 is provided with three sealed doors (not shown), through which access may be had to the upper portion of the interior of the housing. It is also provided with windows (not shown), through which the corona-like discharge and the operation of the machine within the housing may be observed.

Mounted on the top of casing cover 7 are two blowers, an air supply blower 48, and an air exhaust blower 18, both driven by a high-speed motor 19 mounted therebetween. Blowers 18 and 48 and motor 19 are mounted as a unit, one end being supported by an air supply conduit 48', and the other end being supported through an L conduit 17 by a casing head 12, which is centrally positioned on casing cover 7 and is held in place by cap screws 13. Casing head 12 has integral therewith a downwardly extending hollow dead shaft 14 upon which is mounted the stator of an electrode motor 20, the rotor of which is within and carried by a motor casing 22 supported as later described. Extending downwardly from casing 22 is a neck 23, which supports the rotatable lower electrode 34 through a releasable telescopic connection with a hub 25.

Casing head 12 (Figure 1) receives the grain from above through a grain supply conduit 142 and a valve 143, and is provided with a central web 50 structure. This structure forms four downwardly and outwardly extending grain passageways 41 and four upwardly and outwardly extending air exhaust passageways 15 opening into an annular air exhaust manifold 16. Manifold 16 communicates with L conduit 17 of exhaust blower 18, and thus completes an air exhaust circuit which is from hopper 1, up through the center of hub 25, through neck 23, through dead shaft 14, through passageways 15, annular manifold 16, conduit 17, and blower 18 to a suitable exhaust conduit.

Also attached to casing cover 7 by cap screws 13 is a downwardly extending shell 38 which surrounds electrode motor 20 and casing 22, but is spaced throughout so as to form a grain passageway 40 between its inner surface and the outer surfaces of casing 22, neck 23, and hub 25. Electrode 34 is depressed at its center to form a bowl-like portion 36 and shell 38 flares outwardly at its lower end and cooperates with hub 25 in directing the grain outwardly through this bowl-like portion. The outer portion of electrode 34 is provided with a radially extending discharge surface which is substantially the shape 75

of the rim of an inverted dish, or the vertical wall of a truncated cone, and which forms the lower wall of the treatment zone. The grain thus passes from bowl 36 to the inner edge of the discharge surface and then moves outwardly and downwardly through the treatment zone and falls into hopper 1.

Directly above rotatable electrode 34 and spaced therefrom so as to form the upper wall 10 of the treatment zone, is a dome 39 of vitreous dielectric material, such as lower power factor glass or quartz. Dome 39 is provided at its center with a circular opening through which shell 38 extends in definite spaced relationship. The dome is supported at its periphery by a retaining ring 308, which in turn is removably attached to upper housing ring 6 by a plurality of pins 310, which have flattened heads 311. Each pin 310 extends radially inwardly through 20 a hole in housing ring 6 into a vertically elongated hole in retaining ring 308. The flattened head 311 of each pin fits in a suitably shaped recess in housing ring 6 and when band 10 (Figure 1), is properly positioned, it contacts these 25 heads and holds pins 310 in place.

Glued to the periphery of dome 39, and covering the edge and the opposite sides adjacent thereto, is a strip of felt. This felt forms a cushioned seal between dome 39 and retaining 30 ring 308, and the dome is securely held in position without danger of injury thereto by vibration or mechanical stresses.

Under some conditions of usage it is desirable to concentrate and accurately control the discharges, and in the present embodiment these results are obtained by forming ridges upon the discharge surface of electrode 34. These ridges are shown in Figure 2 in the form of five nested Archimedes spirals, each of which extends arcuately substantially 360°, and extends radially across the entire width of the treatment zone. To form these ridges, grooves of the shape shown in Figure 3 are cut in electrode 34, and it is thus seen that the treatment zone is of minimum 45 thickness along these ridges.

As shown best in Figure 3, directly above the discharge surface 37 and upon the upper surface of dome 39, is stationary electrode 42, which is of a few mils thickness. In this embodiment, 50 stationary electrode 42 is made by sand blasting an annular portion of the upper surface of the dome and then covering the sand blasted portion with a layer of lead and a layer of aluminum, the two layers of metal being applied by 55 a metal spray gun, the aluminum being placed over the lead while the lead is still warm. Dome 39 is of uniform thickness and is spaced a predetermined distance from electrode 34. Stationary electrode 42 being in intimate contact with 60 the upper surface of dome 39, is properly spaced from electrode 34, and is of sufficient conductivity and dimensions to function as an electrode, but is thin enough to permit the rapid transfer of heat from dome 39 to the surrounding air.

In operation, a relatively high potential is impressed between stationary electrode 42 and rotatable electrode 34; as the potential increases during a particular half cycle, the potential gradient within the zone rises and it is greatest 65 along the spiral ridges, with the result that spiral zones of corona-like discharges occur along the ridges, the discharges stopping when the potential decreases during the latter part of the half cycle. During successive half cycles discharges 70 occur, but as electrode 34 is rotating rapidly,

these discharges do not occur at the same place within the treatment zone. Thus, when there is a discharge, the heat produced at a particular point within the zone, and within the adjacent portion of dome 39, is dissipated before another 5 discharge occurs at this point.

In considering this particular feature, it will be seen that a point upon a ridge (see Figure 2), such as that designated by the letter X will describe a circle, and that the discharges from 10 this particular point will be distributed around this circle. The various factors, such as the rate of rotation of electrode 34, and the frequency of the high potential, are such that this distribution is uniform throughout the zone, and 15 as a result each point along the surface of dome 39 within the treatment zone is heated substantially the same amount as every other point; this avoids all danger of injury to the dielectric material due to uneven or excessive heating. 20

As indicated above, the thickness of the treatment zone is greater at the inner edge than at the periphery, and in this embodiment this dimension at A is 1.6 times the corresponding dimension at B. As the stream of the product 25 moves through the treatment zone from the center of the electrode structure it tends to slide across the upper surface of the lower electrode, and accompanying it is a predetermined amount of excess air. During the movement toward B 30 the product spreads out, and the amount of the product within a unit area of the zone at B is less than the amount of the product within the same unit area at A. The potential necessary 35 to cause a discharge at a particular point within the zone depends upon the composite dielectric constant of the product and the air at this point. Thus, when the treatment zone is of the same thickness at B as it is at A, with a smaller amount of the product at B, there is a larger 40 amount of air at B, and the composite dielectric constant of this smaller amount of the product and this larger amount of air is different from the composite dielectric constant of the product and air at A. In the present embodiment, the 45 thickness of the zone diminishes between A and B in such a manner as to maintain a ratio between the air and the product to give a sufficiently uniform composite dielectric constant throughout the zone. Thus, as the potential between the two electrode structures increases during a half cycle, discharges occur simultaneously throughout the zone. 50

At the same time, with this construction, the material and the air move through the zone at a 55 uniform rate, so as to minimize the tendency for dust to separate from the product and collect upon the lower surface of dome 39. As a further aid in preventing the accumulation of dust within the treatment zone, wiper plugs are provided 60 upon the rotatable electrode which move adjacent the surface of the dome. The details of construction of these wiper plugs are shown in Figure 3, where a cylindrical plug 400 of dielectric material such as low power factor glass, is 65 shown mounted in an open-bottomed recess 402, in rotatable electrode 34. Recesses 402 are so positioned that the upper ends of plugs 400 are parallel to and spaced from the adjacent surface of dome 39. 70

As electrode 34 rotates, each of plugs 400 describes a circle, and in doing so wipes an annular portion of the adjacent surface of dome 39. Referring to Figure 2, nineteen of these plugs are shown mounted along a spiral line which 75

extends from within the inner edge of the treatment zone through the treatment zone and beyond the periphery thereof; adjacent wiper plugs are so positioned radially with respect to each other that the annular surfaces which they wipe overlap each other, with the result that the entire surface of the dome within and adjacent the treatment zone is maintained free of dust.

Referring to the left-hand side of Figure 3, and the right-hand side of Figure 2, upon the down-turned rim 32 of electrode 34 is adjustably mounted a bar wiper 404, which has a wiper portion 406 in definite spaced relationship with respect to the surface of dome 38 at the periphery of the treatment zone. Rim 32 is provided with a threaded recess 408, in which is mounted a stud 410, which is secured in place by a tapered key 407 (Figure 2). Stud 410 is provided with a central enlarged portion 412 and is threaded at its right end to receive a sleeve nut 414. Bar wiper 404 extends through a notch 416 in rim 32, and it is provided with an upwardly extending shank 418, which is rectangular in cross section and extends through a recess 420 in stud 410. A notched collar 422 is held in contact with shank 418 by nut 414, and thus holds the shank against the left-hand side of recess 420 to rigidly position the wiper bar.

Referring to Figure 2, the wiper bar is illustratively positioned at an angle of 65° from the tangent of the electrode periphery. In the showing of Figure 2 the electrode rotates clockwise, and with the wiper plugs 402 and the wiper bar 406 positioned as shown, dust which may tend to collect within the treatment zone is effectively moved through the zone and discharged with the product.

As shown in Figure 1, carried near the lower end of shell 38 is a triangular insulator 45 which is held in place by a plurality of cap screws 46. Extending through the corners of insulator 45 are three adjustable studs which cooperate to carry upon their lower ends an annular air manifold 44 having an air passageway 409 therethrough. Each stud is held in place by an adjusting acorn nut 304 which is locked by a set screw.

The details of construction of manifold 44 are best shown in Figure 3, there being an upper channel 312, a lower main channel 314, and an inner lower channel 316. Channel 314 is provided with a plurality of interior posts 313 and 315, and channel 312 is provided with cooperating posts 311. Channels 312 and 314 are held together by a plurality of screws 317 which are countersunk and extend through holes in posts 311 and are received in the threaded holes in posts 313. The peripheries of channels 312 and 314 are machined to inter-fit and form a substantial seal. Channel 312 is attached at its inner edge to inner lower member 316 by a plurality of screws 319. The adjacent edges of members 314 and 316 overlap to form an outwardly and downwardly extending slot or jet 52, which is annular, and which directs air outwardly over the surface of stationary electrode 42.

Referring again to Figure 1, attached to the upper side of channel member 312 is a manifold coupling 320 which is held in place by suitable screws and which receives air from air supply blower 48 and conduit 48' through a conduit 47 of dielectric material.

Manifold 44 is effectively insulated from the grounded frame of the machine by members 45 and 47 and at the same time air is delivered through it to the upper surface of the upper

electrode 42. Manifold 44 is rounded at its inner and outer edges and extends beyond stationary electrode 42 so as to statically shield the stationary electrode edges. During operation manifold 44 is at a high potential and the presence of the rounded edges or rims lessens flux concentration and thus avoids the danger of sparking.

In addition to its functions of distributing the air and shielding stationary electrode 42, manifold 44 also provides the high potential electrical connection with the stationary electrode 42. The electrical connection between manifold 44 and stationary electrode 42 is maintained by twelve spring pressed contactors 54 mounted on manifold 44. Each contactor 54 is provided with a head 53 positioned within an enlarged recess in one of posts 313 and contactors extend downwardly through restricted openings beyond the lower surface of the manifold. Above each head 53 is mounted a coil spring 51, which is held in place by one of screws 317. When the elements are in the position shown, coil springs 51 are under tension, and an intimate contact is maintained between the lower end of each contactor 54 and stationary electrode 42.

In Figure 1 the left-hand side of motor 20 is cut away to show the details of construction. Rigidly mounted upon the upper end of dead shaft 14 and held in alignment by a stud 324 is upper frame 60; in a like manner, on the lower end of dead shaft 14 is lower frame 61. These two frames are held in place by a spanner nut 65 which is locked in place on the lower end of dead shaft 14 by a set screw. Frames 60 and 61 provide a support for the electrode motor, casing 22, and the elements supported thereby. Casing 22 includes an upper casing cover 72, a center cylindrical portion 75, a lower casing cover 73, and neck 23. Casing covers 72 and 73 are held in place on the opposite ends of cylindrical portion 75 by a suitable number of cap screws 74. Neck 23 is held in place on the lower end of casing cover 73 by a plurality of cap screws. The upper end of casing cover 72 is provided with a downwardly extending center flange 77 which extends into an annular recess in frame 60, where it is supported by a ball bearing unit 78, mounted on this frame. In a like manner, lower casing cover 73 is provided with a flange 81 which extends downwardly into a recess and is supported by a ball bearing unit 82. The juncture of casing cover 72 and frame 60 is sealed by a dust seal of leather or other suitable material, and the juncture of neck 23 and frame 61 is sealed with a similar dust seal.

Rigidly held in place upon upper frame 60 by clamping ring 62 and a suitable number of cap screws, is a stator core 69 which carries stator winding 64. Surrounding stator core 69 and rigidly clamped between casing covers 72 and 73, is rotor core 71, which is provided with a suitable squirrel cage winding. In this embodiment, a three-phase motor has been used and it has been provided with 48 poles so as to obtain a relatively slow speed at 60 cycles. The conductors 102 from stator winding 64 extend inwardly through a recess (not shown), upwardly along dead shaft 14, and into a junction box 326. Within box 326 conductors 102 are attached to power supply conductors 362, which extend from the source of power, as will be explained below.

Rotatable electrode 34 is removably attached through its hub 25 to neck 23 by means of a centrally positioned screw connection. Thus, neck 75

23 is provided with a spider 28 and depending from spider 28 is a screw threaded stud 27. In a like manner, hub 25 is provided with a spider 30 having a central collar 130, through which extends a sleeve-like nut 29. The lower end of nut 29 is flanged, and is provided with radial slots so that it may be engaged by a wrench. Surrounding the upper end of nut 29 is a collar 31, which acts as a stop to prevent the movement of nut 29 downwardly through collar 130. The lower end of neck 23 flares outwardly and is provided with arcuately extending tapered lugs 432, which extend into similarly shaped slots in hub 25.

15 To install rotatable electrode 34 in position, band 10 is loosened and rested upon lugs 211 on posts 4. The electrode, with its hub 25 and with nut 29 hanging in collar 130, is slid in from the side (the front or near side of Figure 1), on rails 20 5 until hub 25 is directly below neck 23, and nut 29 is directly below stud 27. Nut 29 is then raised until it engages stud 27 and is rotated while electrode 34 is manually held at its periphery so that it cannot rotate. As nut 29 rotates and progresses upwardly on stud 27, the flanged portion of the nut engages the lower surface of collar 130 and lifts electrode 34.

During this engagement of nut 29 with stud 27, stud 27 may tend to rotate due to the fact that it is rotatably supported through spider 28 and neck 23 upon the rotatable motor casing 22. If such rotation occurs, lugs 432 on the lower end of neck 23 will engage and enter the slots in hub 25; at which time rotation of stud 27 will stop because electrode 34 is manually held from rotation. Continued rotation of nut 29 carries electrode 34 and hub 25 upwardly until the hub 25 securely engages the lower end of neck 23; nut 29 is then tightened and electrode 34 is securely supported so that it will be rotated by motor 20.

Mounted in the bottom of hopper 1 is a grating for the purpose of permitting the grain to flow from the hopper, and for preventing, nevertheless, the passage of foreign material, such as pieces of dome 39 if it should break. This grating consists of a series of posts 57 supporting superimposed louvers 58 through which the grain passes. These posts support a cap 59 which directs the grain through the louvers.

50 Extending between vertical posts 4 are two cross-frame members 220 which provide mounting means for a high frequency, low voltage alternator 55 at the right, and control apparatus 85 at the left. Control apparatus 85 includes a control switch 332 which operates switching means to control alternator 55 and the connection of its output, a control switch 334 which operates switching means to start and stop the electrode motor 20 and blower motor 19 which are connected in parallel, an alternator field control rheostat 336, and a wattmeter 338. Mounted on the top of casing cover 7 is a high frequency, high voltage auto-transformer 56, which receives the low voltage, high frequency output of alternator 55, and raises the voltage so that a high voltage, high frequency output is produced and this output is impressed across the electrodes.

70 The three-phase motor circuit of alternator 55 is connected to the control apparatus 85 through conductors 352, and the alternator field of alternator 55 is connected to its rheostat 336 by a pair of conductors 350. As indicated above, electrode motor 20 and blower motor 19 operate in parallel and are connected to the switching means controlled by the control switch 334

through conductors 362. The current coil of wattmeter 338 is connected in conductor 92; one side of its potential coil is connected to conductor 92, and the other side is connected through a potential lead 354 to conductor 94. One side of 5 the output of alternator 55 is connected directly by conductor 94 to the low side of the winding of auto-transformer 56, and this conductor is connected directly at 88 to the grounded frame of the machine. The other side of the output 10 voltage of alternator 55 is connected through switching means (not shown), and through conductor 90 to conductor 92 and thence through low voltage insulator 342 to the tap 96 of the auto-transformer winding. The high side 100 of 15 the auto-transformer is connected by a conductor 344 through a high voltage insulator 346 to manifold 44.

Rotatable electrode 34 is effectively grounded through its supporting means to the frame of 20 the machine and thus, the high frequency, high voltage output of auto-transformer 56 is connected directly across the electrodes. This potential is of such a value that suitable discharges, 25 preferably of disruptive corona-like form, occurs in the treatment zone, which is between the lower surface of disc 39 and discharge surface 37 of the rotatable electrode 34. At the same time, the rounded edges of manifold 44 and the downwardly turned rim 32 at the periphery 30 of rotatable electrode 34 effectively prevent undesirable concentration of flux which might result in sparking.

The switching mechanism controlled by switch 334 is so arranged that alternator 55 cannot be started except when the circuit of blower motor 19 and electrode motor 20 is closed; likewise, alternator 55 will be stopped at any time that the blower and electrode motors are stopped.

During operation, the grain or other material 40 moves down from grain supply pipe 142 through grain valve 143 and through passageways 41. From passageways 41 it passes into passageway 40, where it contacts casing 22 and is given a swirling motion and is conveyed to the upper 45 surface of the rotatable electrode 34. It then passes outwardly and slightly downwardly through the treatment zone to hopper 1, from which it passes by an outlet conduit 2. During the movement of the grain through the treatment zone, it follows turbulent curvilinear paths, 50 so that it is effectively treated and any insect life which is entrained with the grain is sought out by the discharges and destroyed.

As indicated above, when dust accompanies 55 or forms a part of the material being treated, it is desirable for the material to move through the zone without separating the dust from the material. With the present structure, it has been found that this object has been obtained, and 60 the material moves through the zone in an even and uniform manner, and the excessive accumulation of dust upon the surface of dome 39 is avoided.

During the movement of the grain through 65 the treatment zone, air is delivered by blower 48 through conduits 48' and 47, and conduit connection 320 to manifold 44. In passing from manifold 44 through slot 52, the air impinges upon the surface of stationary electrode 42 and 70 moves thereacross; it then escapes to the lower chamber by flowing outwardly from between the inner edge of dome 39 and the lower end of shell 38. At this point, the air is blended with the grain moving outwardly through the treatment

zone, and thus, as the grain passes through the treatment zone, it is accompanied by an additional quantity of air, which is sufficient to bring the dust concentration in the air below that necessary to form an explosive mixture. When air is present in the treatment zone, air-ionization products, including ozone, and certain oxides of nitrogen are formed and these are continually removed along with the heat incident to the process.

10 After leaving the treatment zone, the air moves into the lower part of the housing, and the dust settles from it; it is then withdrawn from the machine by exhaust blower 18, through the center 15 of hub 25, neck 23, dead shaft 14, passageways 16, manifold 16, and L conduit 17. Exhaust blower 18 delivers substantially more air than does air supply blower 48, with the result that a reduced pressure condition is maintained in the lower part 20 of the housing and air is continually being drawn upwardly through grain outlet conduit 2. This air-washes the treated grain, and effectively removes any air-ionization products which might otherwise be trapped and carried downwardly 25 with the grain.

This reduced pressure condition also tends to draw air into the housing through any leaks that might be present. Thus, the air-ionization products and dust accompanying or forming part of 30 the material being treated do not escape to the surrounding area. In one embodiment, it was found that very satisfactory results could be obtained by delivering 200 cubic feet of air per minute from blower 48 and by exhausting 300 cubic 35 feet of air per minute from blower 18.

While the length of discharge gap, which is, in effect, the thickness of the treatment zone, varies with the materials being treated, the voltage, frequency, etc., it has been found that a gap 40 of $\frac{1}{16}$ inch to $\frac{1}{8}$ inch at the inner edge of the zone, with dome 39 of $\frac{3}{8}$ inch thickness, and with a corresponding voltage which ranges from 20,000 volts to 30,000 volts, gives satisfactory results. The length of gap may be varied by 45 changing the length of neck 23. In the present embodiment, the length of gap varies in the radial direction; this variation is of value to maintain the cross-sectional area of the stream of the product and air constant. Thus, the length 50 of gap varies radially through the zone inversely as the diameter; the outside diameter of the zone is approximately 1.6 times the inside diameter and the length of gap at the inner edge of the zone is approximately 1.6 times the length of gap at 55 the outer edge.

A high frequency of 500 cycles per second has been used with excellent results, but lower and higher frequencies may be used. A frequency of 60 cycles has been found satisfactory except that 60 the quantity of material being treated is less; frequencies substantially higher than 500 cycles tend to result in higher dielectric losses and thus excessive heating of dome 39.

When a material such as spring wheat is being treated, and with a flow of 10 bushels per minute, the watt input is on the order of 6400. With a rise in moisture content, this wattage increases, and with lower moisture content, this wattage is correspondingly less.

70 Thus, it is seen that the above mentioned objects are obtained and that a highly efficient and thoroughly practical method and apparatus is provided for treating materials without injury thereto.

75 As many possible embodiments may be made

of the mechanical features of the above invention, and as the art herein described might be varied in various parts, all without departing from the scope of the invention, it is to be understood that all matter hereinabove set forth, 5 or shown in the accompanying drawings, is to be interpreted as illustrative and not in a limiting sense.

I claim:

1. In apparatus of the class described, the combination of, a sheet of dielectric material, a first electrode positioned upon one side of said sheet, a second electrode rotatably mounted upon the other side of said sheet and spaced therefrom to form a treatment zone therebetween, said treatment zone being substantially the shape of the outer enclosing annular surface of a truncated cone, and means to rotate said second electrode to move the product to be treated radially and downwardly through the treatment zone. 20

2. In apparatus of the class described, the combination of, a sheet of dielectric material, a first electrode positioned upon one side of said sheet, a second electrode having a plurality of spirally extending ridges thereon rotatably mounted upon 25 the other side of said sheet and spaced therefrom to form a treatment zone therebetween, said treatment zone being substantially the shape of the outer enclosing annular surface of a truncated cone, and means to rotate said second electrode 30 to move the product to be treated radially and downwardly through the treatment zone.

3. In electrical apparatus in which a product is subjected to an electrical discharge, the combination of, a pair of electrodes, a dielectric plate between said electrodes and spaced from one of said electrodes so as to form a treatment zone, said treatment zone being substantially the shape of the enclosing annular surface of a truncated cone, an air manifold having a jet adjacent one of 40 said electrodes, and means to deliver air from said manifold through said jet into heat-conducting relationship with said dielectric plate and through said treatment zone. 35

4. In an electrical apparatus in which a product is moved onto a rotatable electrode and is moved along a surface of said electrode through a treatment zone, the combination of, a pair of electrodes, and a sheet of solid dielectric material positioned between said electrodes and forming an annular treatment zone between it and one of said electrodes, said one of said electrodes having an active discharge surface extending spirally along the lower surface of the treatment zone and being rotatable to move the product to 50 be treated over said active discharge surface. 45

5. In electrical apparatus, the combination of, a member of dielectric material, a first electrode positioned upon one side of said member, and a second electrode upon the other side of said member and spaced therefrom, said second electrode having an active discharge surface which comprises an enclosing ridge construction formed by a plurality of nested Archimedes spirals. 60

6. In apparatus of the character described, an annular electrode comprising a plate the active surface of which is formed by an annular metallic ridge construction comprising a plurality of ridges, each of said ridges extending a substantial distance in a radial direction. 65

7. In apparatus of the class described, an annular electrode having a substantially frustoconical discharge surface formed by a plurality of spirally extending active discharge areas. 70

8. In apparatus of the class described, the 75

- combination of, a pair of wall constructions, one of said wall constructions comprising a sheet of dielectric material and the other of said wall constructions comprising the active discharge portion of an electrode, said wall constructions converging radially to define a treatment zone the thickness of which varies inversely as the radius.
9. In apparatus of the class described, the combination of, an electrode rotatably mounted and having an annular upper surface which forms the lower wall of a treatment zone, a sheet of dielectric material mounted above said electrode in spaced relationship thereto and forming the upper wall of said treatment zone, and means to move a product to be treated outwardly through said treatment zone, said walls converging from the inner edge to the outer edge of said treatment zone.
10. In electrical apparatus of the type where 20 in a material is subjected to discharges within a treatment zone, the combination of, a sheet of dielectric material, an electrode mounted in intimate contact with one surface of said sheet, an air manifold having an elongated jet construction impelling a sheet of air across said electrode, and an elongated contactor resiliently mounted on said manifold adjacent said electrode and forming an electrical connection therewith.
11. In apparatus of the class described, the combination of, a sheet of dielectric material, a first electrode positioned upon one side of said sheet, a second electrode rotatably mounted upon the other side of said sheet and spaced therefrom to form a treatment zone therebetween, wiper 35 means of dielectric material mounted upon said second electrode and extending into operative relationship with respect to said sheet.
12. In apparatus of the class described, the combination of, a sheet of dielectric material, a first electrode positioned upon one side of said sheet, a second electrode rotatably mounted upon the other side of said sheet and spaced therefrom to form a treatment zone therebetween, a cylindrical plug of dielectric material mounted on said 45 second electrode and extending into the treatment zone with one end wall positioned adjacent the surface of said sheet.
13. In apparatus of the class described, the combination of, a sheet of dielectric material, a first electrode positioned upon one side of said sheet, a second electrode rotatably mounted upon the other side of said sheet and spaced therefrom to form a treatment zone therebetween, a plurality of wiper plugs mounted on said second 55 electrode with their axes substantially at right angles to the adjacent surface of said sheet, said plugs being mounted along a spiral line extending through said treatment zone.
14. In apparatus of the class described, the combination of, a sheet of dielectric material, a first electrode positioned upon one side of said sheet, a second electrode rotatably mounted upon the other side of said sheet and spaced therefrom to form a treatment zone therebetween, a wiper bar of dielectric material mounted on said second electrode and positioned adjacent the surface of said sheet at one edge of said treatment zone.
15. In apparatus of the class described, the combination of, a sheet of dielectric material, a first electrode positioned upon one side of said sheet, a second electrode rotatably mounted upon the other side of said sheet and spaced therefrom to form a treatment zone therebetween, a plurality of wiper members mounted on said sec-
- ond electrode along a curvilinear line extending through said treatment zone, and a wiper bar mounted on said second electrode with its outer end trailing with respect to the direction of rotation of said second electrode, said wiper bar being positioned adjacent the periphery of said treatment zone.
16. In apparatus for treating bulk material within a treatment zone by subjecting it to the discharges resulting from impressing a high potential across a pair of electrode structures, the combination of, a wiper bar of dielectric material having a shank rigid therewith, and means mounting said wiper bar to move along one wall of the treatment zone at the place where the treated product is discharged, said last-named means including a stud having an opening therethrough to receive said shank and a sleeve-nut construction rotatably mounted on said stud to rigidly clamp said shank in said opening. 20
17. In the art of treating bulk materials by passing them through an annular treatment zone wherein said materials are subjected to electrical discharges, the steps of, delivering the material to be treated at a substantially uniform rate to the center of the treatment zone, delivering a predetermined quantity of a gas to said center of said treatment zone, creating forces upon the material and upon the gas to cause both of them to move through the treatment zone together at a substantially uniform rate, and maintaining substantially uniform proportions of gas and the material being treated throughout said treatment zone.
18. In electrical treating apparatus in which a product is moved through an annular treatment zone and subjected to discharges within said zone, the combination of: a pair of electrode structures; and a sheet of solid dielectric material positioned between said electrode structures and forming an annular treatment zone with one of said electrode structures; said one of said electrode structures having an annular surface adjacent the treatment zone which is generally the shape of the outer surface of a truncated cone, and which is terraced to form a plurality of ridges across which the material passes. 35
19. In apparatus for treating bulk materials in which the material is moved to the center of a substantially disc-like electrode structure and is caused to move by the rotation of the electrode structure outwardly through an annular treatment zone, a substantially disc-like electrode structure having an annular active discharge surface, and a plurality of arcuately extending ridges extending along said active discharge surface to produce a terraced effect. 50
20. In an electrical apparatus in which a material is moved onto a rotatable electrode and is moved along a surface of said electrode through a treatment zone, the combination of: a pair of electrode structures; a sheet of solid dielectric material positioned between said electrode structures and forming an annular treatment zone between it and one of said electrode structures, one of said electrode structures having an active discharge surface extending substantially spirally along one surface of the treatment zone; and means to cause relative movement between said sheet of dielectric material and said electrode structure having a spirally extending active discharge surface whereby the distribution of discharges within the treatment zone is accurately controlled. 65
21. In electrical treating apparatus, the com- 70
- 75

- bination of, an annular electrode comprising a thin metallic sheet, and air directing means including a wall spaced from but extending along the surface of said electrode and a jet moving air 5 against one edge of said electrode and between said electrode and said wall to the other edge of said electrode.
22. In electrical treating apparatus, the combination of, an annular metallic electrode, an 10 annular wall construction spaced from said electrode and providing an annular passageway therebetween, and an annular jet adjacent one edge of said electrode and impinging a sheet of air into said passageway toward the other edge of 15 said electrode; whereby a sheet of air moves across said annular electrode from one edge to the other.
23. In electrical treating apparatus, the combination of, a thin metallic electrode mounted 20 upon one side of a dielectric plate, a rigid metallic member extending along said electrode, and a spring-pressed plunger mounted in said rigid metallic member and having a protruding end resiliently pressed against said electrode; where- 25 by an electrical connection is maintained between said rigid metallic member and said electrode.
24. In apparatus of the class described, the combination of, an electrode rotatably mounted and having an annular upper surface which forms 30 the lower wall of a treatment zone, and an upper wall construction positioned above said electrode in spaced relationship thereto and forming the upper wall of said treatment zone, said upper wall construction having means associated therewith constituting an upper electrode structure, said upper surface of said electrode and said wall construction converging radially to thereby limit said treatment zone so that the thickness of said treatment zone varies inversely as the radius. 5
25. In an electrical apparatus in which a product is treated in a treatment zone by subjecting 10 it to the discharges resulting from impressing a high potential across a pair of electrode structures, the combination of, a dome of dielectric material, a pair of annular electrode structures positioned upon opposite sides of said dome and 15 having substantially coextensive discharge surfaces, one of said electrode structures being positioned substantially within said dome and having an outer surface spaced from the inner surface of said dome to thereby define an annular treat- 20 ment zone between said outer and inner surfaces.
26. In apparatus of the class described, the combination of, a pair of wall constructions, one of said wall constructions comprising a dome of dielectric material, and the other of said wall con- 25 structions comprising the active discharge portion of an electrode, said constructions converging radially to define a treatment zone the thickness of which varies inversely as the radius. 30

FRANKLIN S. SMITH.
